No. 800,916.

PATENTED OCT. 3, 1905.

E. M. HEWLETT & W. L. R. EMMET.

HIGH POTENTIAL SWITCH.

APPLICATION FILED JAN. 15, 1900.

UNITED STATES PATENT OFFICE.

EDWARD M. HEWLETT AND WILLIAM L. R. EMMET, OF SCHENECTADY,
NEW YORK, ASSIGNEES TO GENERAL ELECTRIC COMPANY, A CORPO-
RATION OF NEW YORK.

HIGH-POTENTIAL SWITCH.

No. 800,916.

Specification of Letters Patent.

Patented Oct. 3, 1905.

Application filed January 15, 1900. Serial No. 1,461.

To all whom it may concern:

Be it known that we, EDWARD M. HEWLETT and WILLIAM L. R. EMMET, citizens of the United States, and residents of Schenectady, 5 county of Schenectady, State of New York, have invented certain new and useful Improvements in High-Potential Switches, of which the following is a specification.

The object of this invention is to provide a 10 switch for high-potential electric currents, and particularly such as may be employed in central or distributing stations for handling currents of large amperage.

In carrying out the invention we mount upon 15 an insulating-support, such as a switchboard, a frame carrying fixed and movable circuit- terminals and inclose the latter in a movable pot or well of oil or other insulating liquid and provide means for rocking the circuit- 20 closing contact into operative relation to a desired set of terminals.

The invention embodies various structural features, the novelty of which will be hereinafter fully described and will be definitely 25 indicated in the claims.

In the accompanying drawings, illustrating the invention, Figure 1 is a sectional elevation of a double-throw multipolar switch embodying our improvements. Fig. 2 is a sectional 30 view on a plane at right angles to that shown in Fig. 1. Fig. 3 is a diagrammatic view of the circuit connections.

1 represents a support of insulating material, which may be a switchboard and formed 35 of marble, slate, or other fireproof insulating material. In the rear of this support is mounted a cast-iron frame 2, comprising a horizontal plate which forms the top of the oil-receptacle, and depending arms 3 3^a, supporting 40 the fixed and movable elements of the switch. On this plate is hung a well or pot 4 for oil or other insulating liquid which may be employed, which we prefer to pivot at one side, as indicated at 5, and provide with a detachable 45 clamp at the other side adapted to be thrown into or out of clamping relation to a slotted ear or lug on the supporting-frame. In the arms 3 3^a is journaled an iron frame 7 in the form of a shell, in which is secured a wooden 50 support 8 for the movable contacts of the switch. Secured to the lower part of the arms 3 3^a are wooden supports 9 9^a for the fixed circuit-terminals.

The movable element is provided with a crank 10, formed integral with the shell 7, 55 which is connected by links with a crank on the rock-shaft 11, another arm of which is connected to an operating-lever 12 on the front of the support, the arm passing through an opening in the support. A stop 13, carried by 60 the arm, is placed in position to engage the supporting-frame and arrest movement of the parts at the forward limit of movement of the operating-lever 12. A knob 14 on the front of the support connects by a rod with a bell- 65 crank lever 15, which raises or permits to descend a spring-pressed pin 16, adapted to engage a notch 17 in a part of the shell which carries the movable parts of the switch, (seen in Fig. 2,) the notch being so placed that it holds 70 the switch in its open position. The circuit- terminals pass through insulators or bushings, as 18, of porcelain, supported in the top plate of the oil-well, and may be clamped in their seats by a lead joint 18' or in any other suitable way. The circuit leads pass through the insulators and are in conductive relation to 75 elastic clips 19 19^a, firmly fixed to the blocks 9 9^a. Any desired number of these clips may be employed according to the character of 80 the circuits or the number of poles of the switch. In the drawings we have shown a double-pole two-throw switch suitable for a high-potential triphase alternating-current circuit. Each pole is independently mounted 85 and its point of rupture inclosed between insulating-barriers, as 20 20^a, &c., composed of plates of indurated fiber or other fireproof insulator supported in the blocks 9 9^a and extending across the oil-well to afford a fire- 90 proof wall on each side of the contact extending from side to side of the oil-well. The top of the barriers may be cut away to permit free movement of the rocker, on which the bridge-pieces which connect the several poles 95 are mounted. These bridge-pieces are composed of good conducting metal, of inverted-U shape, bolted to the wooden rocker and shifted into engagement with the clips at either side of the oil-well. Each limb of the 100 bridge acts as a knife-switch to enter the clips which constitute the pole of the fixed member. This will be clearly seen from Fig. 2, where 21 21^a represent the two limbs of the bridge engaging the clips 19. 105

The relation of the circuit-terminals will

be clearly understood from an inspection of Fig. 3, where they are shown in diagram. In this figure, $a b c$ represent the supply-circuit, and $a' b' c'$ and $a'' b'' c''$ two distributing-circuits with which connection may be made by the switch with the supply-circuit. Each limb of the supply-circuit connects with one jaw of two insulated clips, one limb on each side of the switch in parallel, the co-operating jaw of the clip being connected with corresponding leads of the two distributing-circuits. Thus when the switch is thrown so as to connect the supply-circuit $a b c$ to the distributing-circuit $a' b' c'$ the bridge-pieces connect each phase of the supply-circuit at a double-pole contact with a lead of the distributing-circuit.

In mounting the parts for operation the well 4 is filled with oil or other insulating liquid to a sufficient depth to cover the operative parts when in position and is then pushed up snugly against the support and locked in position. When the circuit is opened, the switch is in the position indicated in full lines in Fig. 1 and is held against movement in that position by the stop-pin 16. When it is desired to cut in either distributing-circuit, the knob 14 is pulled out, releasing the catch, and the operating-lever 12 pushed in or pulled out to its full limit, thereby connecting the main with one or the other distributing-circuit. The best results are attained when the oil submerges not only the contacts, but the rocker-frame 7 as well, so that all live parts of the switch are under oil.

What we claim as new, and desire to secure by Letters Patent of the United States, is—

1. A circuit-breaker comprising a base, a movable part, and a support for said two parts, said base and movable part being provided with co-operating make-and-break contacts, combined with a detachable oil-insulator adapted to be placed in position for immersing said contacts without disturbance of the said mechanism.

2. An oil-switch comprising a support for fixed and movable electrodes, and an oil-well inclosing the electrodes and adapted to be raised and lowered with relation thereto.

3. An oil-switch comprising a support for the fixed and movable electrodes, and an oil-well inclosing the electrodes pivoted at one side and provided with a catch for holding or releasing it.

4. In an electric switch, the combination of a horizontally-disposed supporting-plate, fixed contacts mounted thereon, and a receptacle for containing an insulating fluid, said receptacle detachably suspended from said supporting-plate.

5. In an electric switch, the combination with a horizontal supporting-plate, of side plates depending therefrom, insulating-bars

connecting said side plates, and a series of 65 spring-contacts mounted on said bars.

6. In an electric switch, the combination with a horizontal supporting-plate, of side plates depending therefrom, insulating-bars 70 connecting said side plates, a series of spring-contacts mounted on said bars, an oscillating cylinder pivoted in said side plates, and a series of knife-blades carried by said cylinder.

7. In an electric switch, the combination with a switchboard, a horizontal supporting-plate 75 projecting from the back of the switchboard, side plates depending therefrom, insulating-bars connecting said side plates, a series of spring-contacts mounted on said bars, an oscillating cylinder journaled in said side 80 plates, a series of knife-blades carried by said cylinder, an operating-handle on the front of the switchboard, and mechanism introduced between the handle and the cylinder for oscillating the cylinder.

8. In an electric switch, the combination with a switchboard, a horizontal support projecting from the back of the switchboard, switch mechanism depending from said horizontal support, and a well of insulating liquid 90 also depending from said support and submerging said switch mechanism.

9. An oil-switch comprising a support, fixed circuit-terminals mounted thereon, a rocking terminal adapted to close or open the 95 switch, an oil-well adapted to be withdrawn from the terminals without disturbing them, submerging the terminals in a bath of insulating liquid through the range of movement of the movable switch element, and an operating-handle for rocking the movable element.

10. An oil-switch comprising a support for the fixed circuit-terminals, on the rear of the switchboard, a rocking bridge to connect the terminals, a removable oil-well inclosing the 105 terminals, an operating-handle on the front of the board, and a latch to lock the switch in closed or open position.

11. An electric switch comprising a supporting-frame on the rear of an insulating-support, multiple-pole circuit-terminals fixed thereto, a rocking frame carrying bridge-pieces to connect a plurality of sets of terminals for different circuits, a handle for operating the frame from the front of the support, and a well of insulating liquid covering the contacts.

12. An electric switch comprising an insulating-support, two or more fixed groups of multiple-pole circuit-terminals mounted in a frame secured to the back of the support, a rock-shaft on the frame, bridge-pieces carried thereby to connect the several groups of terminals, a removable oil-well submerging the terminals in a bath of insulating liquid, a handle on the front of the support, and a stop to check the rock-shaft in the open position of the switch.

13. An oil-switch comprising fixed terminals, a support therefor, a rocker-frame carrying circuit-closing devices and an oil-bath submerging the terminals and all live parts of 5 the switch, said bath being adapted to be withdrawn without disturbing the terminals.
14. An electric switch comprising multipolar circuit-terminals, a fixed support therefor, a removable bath of oil submerging the same 10 capable of withdrawal without disturbing the contacts and insulating-barriers mounted on the support at each side of the terminals in the oil separating the several poles and surrounding them with solid insulating-walls.
15. An electric switch comprising multipolar circuit-terminals mounted on fixed insulating-supports, an oil-well inclosing the terminals and removable therefrom without disturbing the electric connections, and barriers 15 of insulating material separating the adjacent 20 poles.
16. An electric switch comprising a plurality of fixed multipolar terminals mounted on fixed insulating-supports, a rocking circuit-closing device, barriers of insulating material between the several poles mounted on the insulating-supports and inclosing the several terminals between solid insulating-walls, and an oil-bath submerging all live parts capable of removal without disturbing the terminals. 25 30

In witness whereof we have hereunto set our hands this 12th day of January, 1900.

EDWARD M. HEWLETT.
WILLIAM L. R. EMMET.
